AUTOMATIC DRINK DISPENSER

Joel D. Fogel, 10764 N. Kendall Drive, Apt. 14,
Miami, Fla. 33156

Filed June 15, 1972, Ser. No. 263,237

Term of patent 14 years

Int. Cl. D15—01

U.S. Cl. D94—3 B

FIG. 1

FIG. 3

FIG. 1 is a perspective view of an automatic drink dispenser showing my new design;

FIG. 2 is a front elevational view; and

FIG. 3 is a right side elevational view.

The rear surface, not shown, is smooth and flat.

I claim:

The ornamental design for an automatic drink dispenser, substantially as shown and described.
